[57] **CLAIM**

The ornamental design for lighter, as shown and described.

DESCRIPTION

FIG. 1 is a front, top and right-side perspective view of a lighter, with the top cover open, showing my new design;

FIG. 2 is a front elevational view thereof;

FIG. 3 is a right-side elevational view thereof;

FIG. 4 is a rear elevational view thereof;
FIG. 5 is a left-side elevational view thereof;
FIG. 6 is a top plan view thereof;
FIG. 7 is a bottom plan view thereof;
FIG. 8 is a front, top and right-side perspective view of a lighter with the top cover open, showing a second embodiment of my new design;
FIG. 9 is a front elevational view thereof;
FIG. 10 is a right-side elevational view thereof;
FIG. 11 is a rear elevational view thereof;
FIG. 12 is a left-side elevational view thereof;
FIG. 13 is a top plan view thereof;
FIG. 14 is a bottom plan view thereof;
FIG. 15 is a front, top and right-side perspective view of a lighter, with the top cover closed, showing a third embodiment of my new design;
FIG. 16 is a front, top and right-side perspective view thereof, with the top cover open;
FIG. 17 is a rear, bottom and right-side perspective view thereof, with the top cover open;
FIG. 18 is a rear, top and left-side perspective view thereof, with the top cover open;
FIG. 19 is a front, top and right-side perspective view of a lighter, with the top cover closed, showing a fourth embodiment of my new design;
FIG. 20 is a front, top and right-side perspective view thereof, with the top cover open;
FIG. 21 is a rear, bottom and right-side perspective view thereof, with the top cover open; and
FIG. 22 is a rear, top and left-side perspective view thereof, with the top cover open.
FIG. 23 is an upper left and rear side perspective view of the first embodiment with the cover in the open position;
FIG. 24 is an upper left and rear side perspective view of the second embodiment with the cover in the open position.
